UNITED STATES PATENT OFFICE.

WILLIAM H. PAVITT, OF BROOKLYN, NEW YORK, ASSIGNOR OF ONE-THIRD TO LOUIS WILPUTTE AND TWO-THIRDS TO ALICE A. WILPUTTE, BOTH OF NEW ROCHELLE, NEW YORK.

COKE OVEN.

Application filed May 5, 1922. Serial No. 558,642.

To all whom it may concern:

Be it known that I, WILLIAM H. PAVITT, a citizen of the United States, and a resident of Brooklyn, in the county of Kings and State of New York, have invented certain new and useful Improvements in Coke Ovens, of which the following is a specification.

My present invention relates to coke ovens of the type in which the heating walls at the sides of the oven chambers or retorts are provided with heating flues the walls of which are separate from masonry retaining walls between which and the oven chambers proper the flues are interposed. In this type of construction, which is one commonly employed in horizontal flue coke ovens, the wall separating each adjacent pair of retorts comprises a central section, which I shall hereinafter refer to as the supporting wall, and which may be regarded as forming a portion of the masonry framework of the oven battery, and separate flue containing sections, which I shall hereinafter refer to as heating walls, located one at each side of the supporting wall, and each such heating wall interposed between the supporting wall and the adjacent coking chamber. The heating walls are sometimes hotter and sometimes colder than the supporting wall and this results in relative expansion and contraction of the supporting and heating walls.

Largely as a result of this relative expansion and contraction and of the fact that the bricks forming the heating walls are comparatively thin to facilitate the transmission of heat from the heating gases in the flue to the coal being coked, great difficulty has heretofore been experienced from leakage through the joints in the end portions of the heating walls; and the primary object of my present invention is to provide an improved construction of the end portions of the heating walls in a coke oven construction of the type referred to whereby leakage is wholly or largely avoided.

The various features of novelty which characterize my invention are pointed out with particularity in the claims annexed to and forming a part of this specification. For a better understanding of the invention, however, and the advantages possessed by it, reference should be had to the accom-

panying drawings and descriptive matter in which I have illustrated and described a preferred embodiment of my invention.

Of the drawings:

Fig. 1 is a side elevation of a portion of a coke oven structure;

Fig. 2 is a partial section on the line 2—2 of Fig. 1;

Fig. 3 is a partial section on the line 3—3 of Fig. 2;

Fig. 4 is a partial section on the line 4—4 of Figs. 1 and 2; and

Fig. 5 is a partial section on the line 5—5 of Fig. 4.

In the coke oven structure illustrated in the drawing, A represents the masonry skeleton or body of the coke oven structure which comprises horizontally elongated retorts B. Each adjacent pair of retorts B are separated by masonry comprising a central supporting wall C, which may be regarded as forming a portion of the masonry skeleton of the oven structure, and heating walls D one at each side of the supporting wall C, and each interposed between the latter and the adjacent retort. The opposite side walls of each retort B are thus formed by the two heating walls D which form linings, so to speak, for the two adjacent supporting walls C. Each heating wall D comprises side walls formed of comparatively thin bricks D', and D², bricks D³ forming the horizontal flue division walls, bricks D⁴ and D⁵ forming the top and bottom walls, respectively, of the flue space, and bricks D⁶ forming the ends of the heating wall.

In the well known horizontal flue system illustrated in the drawings, gas is supplied at one end of each of the horizontal flues D' except the lowermost flue, by a corresponding gas supply pipe E which is inserted in a gas inlet passage E' formed in the corresponding end brick D⁶. Valves E² or other regulating provisions are made for controlling the flow through the various gas inlets. Air for the combustion of the gas is introduced into the heating walls adjacent each gas inlet E' through a corresponding port C' from an air supply channel C² of which there is one formed at each end of the each supporting wall C, and each of which receives preheated air at its lower end from a recuperator or regenerator sys-

tem below the level of the retorts and not shown in the drawings. The products of combustion escape from each hollow heating wall through a port D^s opening through the bottom wall of the lowermost horizontal flue D^7 and communicating with a port or channel formed in the masonry framework of the oven structure and leading to the recuperator or regenerative system.

10 In so far as above described the structure shown is of a type well known and in extensive use. The structure shown differs from the constructions heretofore known, however, in the shape and relative arrangement of the bricks forming the ends of the heating walls, and comprises a novel form of metallic armor for the side walls of the oven structure, and provisions whereby this armor and the specially shaped and disposed bricks forming the ends portions of the heating walls cooperate to maintain tight joints in said walls.

As shown the heating wall end bricks D^s each comprises a tongue portion d and an enlarged head comprising shoulder portions d' and d^2 projecting laterally away from the tongue portion d . The tongue portions d of the bricks D^s extend between the bricks D' and D^2 forming the sides of the hollow heating walls, and the shoulders d' and d^2 abut against the front edges of the bricks D' and D^2 . The shoulders d' and d^2 of each brick D^s extend laterally away from the tongue d distances less, respectively, than the thickness of the bricks D' and D^2 .

At each end of each heating wall D is placed a metallic flashplate or armor member F which is held against lateral movement away from the corresponding supporting wall C , and has one flared side F' projecting beyond the corresponding end brick shoulders d' , and fitting against the flared or bevelled edges D^s of the corresponding bricks D' . In consequence of the construction described, each armor member F , when in place as shown in Figs. 1 and 4, not only holds the end bricks D^s against the outer edges of the bricks D' and D^2 but also holds the heating wall D against the supporting wall C with a wedging action and thus prevents any spreading movement of either the bricks D' or the bricks D^2 away from the interposed tongue portion d of the bricks D^s . Preferably, as shown, the flashplate members F are trough-shaped, and each comprises in addition to the side F' a similar oppositely flared side F^2 which projects beyond the shoulders d^2 of the corresponding end bricks D^s , and engages the bevelled edges D^4 of the bricks D^2 , so that each armor member F when pressed inward against the bricks D^s positively holds the bricks D' and D^2 snugly against the tongue portions d of the bricks D^s .

65 The provisions shown for holding the ar-

mor member F against movement away from the corresponding central supporting wall C comprise adjustable wedges G interposed between the member F and bracket arms H' secured to the oven buckstays H . As shown 70 the oven buckstay H at each end of the supporting wall C comprises a pair of channel bars which are bolted together and to which the brackets H' are secured. Interposed between each buckstay and the adjacent end of 75 the supporting wall C is a flashplate K a little narrower than the wall C against which it is placed. The two armor members F at the opposite sides of each end of each coking chamber B are spaced apart by interposed top lintel members L which may be formed and connected to the armor members F in a known manner. At the lower end the two members F at the opposite sides of the coking chamber may be spaced apart by the 80 metallic floor sill members M . In lieu of or in addition to the described means for spacing the opposed members F apart, and thereby holding the ends of the heating walls D against the adjacent retaining walls C , other 85 means may be employed for holding the armor members F against movement away from the adjacent retaining walls. Special provisions for this purpose are not really required however to maintain tight joints between the bricks D' and D^2 and the bricks D^s , when the members F are of the preferred construction illustrated, since with this construction, the bricks D' and D^2 are held by the sides F' and F^2 snugly against the tongue 90 portions d of the bricks D^s , thus insuring tight joints.

Advantageously the outer edges of the sides F' of the armor members F are so shaped relative to the metallic framework 105 or rim of the corresponding coke oven door I as to provide a suitable space for luting material N sealing the joints at the margin of the door when the latter is in place. Advantageously also the adjacent edges of the 110 flashplates K and armor members F are shaped to provide a space for luting material O , which prevents leakage of air into or gases out of the oven passages or channels through the adjacent brickwork joints. The horizontally elongated character of the joints between the bricks D^s and the bricks D' and D^2 , as well as the fact that in the preferred construction illustrated the sides F' and F^2 115 of the members F cover the outer edges of these joints contributes to the avoidance of objectionable leakage. Advantageously, as shown, the doors I are provided with locking bars working in slotted brackets carried by the door and engaging inclined shoulders 120 H^2 formed at the ends of corresponding bracket arms H . The gas piping E' supplying gas to the burner nozzles E are branches from the gas supply main E^s , these branches 125 extending upward at the sides of the buck- 130

stays and passing through apertures provided for the purpose in stiffening rib portions of the bracket arms H.

While in accordance with the provisions 5 of the statutes I have illustrated and described the best form of embodiment in my invention now known to me, it will be apparent to those skilled in the art that changes may be made in the form of apparatus disclosed without departing from the 10 spirit of my invention as set forth in the appended claims, and that in some cases certain features of my invention may be used to advantage without a corresponding use of 15 other features.

Having now described my invention, what I claim as new and desire to secure by Letters Patent, is:

1. In a coke oven of the type in which 20 a central supporting wall and separate hollow heating walls at opposite sides of the supporting wall are interposed between each adjacent pair of coking chambers, the improvement which comprises a metallic 25 armor member at the end of each heating wall and engaging the end and outer side wall bricks thereof and means holding each of said armor members against movement away from the adjacent central supporting 30 wall.

2. In a coke oven, the combination comprising a central supporting wall and separate hollow heating walls at opposite sides of the supporting wall and forming the 35 adjacent side walls of an adjacent pair of coking chambers, and a metallic armor member at the ends of each heating wall engaging the inner and outer side wall bricks thereof with a wedging action to prevent 40 their separation.

3. In a coke oven of the type in which a central supporting wall and separate hollow heating walls at opposite sides of the supporting wall are interposed between each 45 adjacent pair of coking chambers, the improved heating wall end construction comprising inner and outer side wall bricks, end wall bricks comprising tongue portions in-

terposed between the side wall bricks, a trough shaped metallic armor member at 50 the end of the heating wall with side portions engaging the side wall bricks and holding them against said interposed tongue portions, and means for anchoring said armor members in place. 55

4. In a coke oven of the type in which a central supporting wall and separate hollow heating walls at opposite sides of the supporting wall are interposed between each adjacent pair of coking chambers, the improved 60 heating wall end construction comprising inner and outer side wall bricks, end wall bricks comprising tongue portions interposed between the inner and outer side wall bricks, a trough shaped metallic armor 65 member at the end of the heating wall with side portions engaging the side wall bricks and holding them against said interposed brick portions, and means for holding said armor member in fixed relation to the adjacent 70 supporting wall.

5. In a coke oven of the type in which a central supporting wall and separate hollow heating walls at opposite sides of the supporting wall are interposed between each 75 adjacent pair of coking chambers, the combination with the bricks forming the inner and outer side walls at each end of each heating wall, of bricks at the end of the heating wall comprising tongue portions interposed between said inner and outer side wall bricks, a trough shaped metallic armor member at each end of each heating wall comprising side portions engaging the corresponding inner and outer side wall bricks, 80 a metallic armor member anchored against each end of each central supporting wall, and mechanical connections between the armor at each end of each supporting wall and the adjacent trough shaped armor members at the ends of the heating walls. 85

Signed at New York in the county of New York and State of New York this 4th day of May A. D. 1922.

WILLIAM H. PAVITT.

CERTIFICATE OF CORRECTION.

Patent No. 1,521,123.

December 30, 1924.

WILLIAM H. PAVITT.

It is hereby certified that error appears in the above numbered patent requiring correction as follows: In the grant, line 13, strike out the name and comma "William H. Pavitt,"; and that the said Letters Patent should be read with this correction therein that the same may conform to the record of the case in the Patent Office.

Signed and sealed this 18th day of March, A. D. 1941.
